UNITED STATES PATENT OFFICE.

MOSES CHERRY, JR., OF LARCHMONT MANOR, NEW YORK.

TRUNK.

1,137,257.

Specification of Letters Patent. Patented Apr. 27, 1915.

Application filed June 2, 1913. Serial No. 771,203.

To all whom it may concern:

Be it known that I, Moses CHERRY, Jr., a citizen of the United States, and a resident of Larchmont Manor, in the county of Westchester and State of New York, have invented a new and Improved Trunk, of which the following is a full, clear, and exact description.

My invention relates to improvements in trunks, and has reference more particularly to an adjustable support adapted to carry the corner of a tray, or a hat or a similar object.

An object of the invention is to provide an inexpensive, simple, strong and reliable trunk which can be utilized with a tray, as an ordinary trunk, or as a hat trunk.

Another object of the invention is to provide a trunk in which the supports for hats, when used as a hat trunk, can be so adjusted as to admit hats of different size and in any desired part of the trunk.

A further object of the invention is to provide a trunk in which the supports, when used as an ordinary trunk with a tray, will allow the adjustment of the tray at any desired distance from the bottom of the trunk.

A still further object of the invention is to provide a trunk which will carry hats and trays above the same without interference.

Another object of the invention is to provide a trunk with a collapsible tray which, when not in use, rests in the bottom of the trunk.

The invention consists of the construction and combination of parts to be more fully described hereinafter and fully set forth in the claims.

Reference is to be had to the accompanying drawings forming a part of this specification, in which like characters indicate corresponding parts in all the views and in which:

Figure 1 is a perspective fragmentary section of the lower portion of a trunk embodying my invention; Fig. 2 is a view of the standard provided with a hat support, as seen in the direction of the arrow 2 on Fig. 3; Fig. 3 is a section on line 3-3, Fig. 1; Fig. 4 is a section on line 4-4, Fig. 2; Fig. 5 is a section through the clamp provided with a support for a tray; and Fig. 6 is a perspective view of a trunk showing the lid raised and indicating the position of a standard provided with a hat support.

Referring to the drawings, 7 indicates the trunk, which is provided with a corner rail 8 secured to the walls and bottom of the trunk in any suitable way; see Fig. 6. The rail 8 is provided at each side with a series of openings 9 and 10 respectively, the opening 9 being staggered with respect to opening 10. Engaging the opening 9 of the rail 8 by means of a beveled end 11 is a standard 12. The standard 12 is preferably made of wood or fiber. The opposite end of standard 12 is provided with a U-shaped member 13. The U-shaped member is secured to the standard with one side, the opposite side overhanging the upper edge of the side wall of the trunk. It is understood that the beveled edge 11 of the standard 12 must be forced into the opening 9 before the U-shaped member 13 contacts with the edge 70 of the side wall of the trunk.

Engaging the standard 12 is a channel member 14, the width of the channel being substantially equal to the width of the standard 12, and the depth of the channel member 14 being substantially equal to the thickness of the standard. The channel member 14 is provided at one end with projections 15 extending above the standard 12 at each side thereof and at the other end with a cross member 14' forming a loop engaging the standard. Pivots 16, mounted in the projections 15 is a lever 16, which has the end 17 adjacent the pivots provided with teeth so that the same will engage with the standard when the lever is in position indicated in the drawings. The opposite end 18 of the lever 16 is raised so that when the lever engages the standard, as shown in drawings, and the standard is 95 in position indicated in Figs. 1 and 6, the wall adjacent the standard will prevent the lever from disengaging itself from the standard. This end is also provided with a pin 18' registering in an opening 24 provided in the cross member 14'. This pin is also adapted to register with the openings 25 provided in the standard. This engagement between the pin and the standard makes the connection between the two positive, that is, it prevents a sliding motion of the channel member 14. Furthermore, the end 17 of the lever is slightly eccentric with respect to the pivots of the lever, so that when it is closed its tendency is to maintain 110 the lever in engagement with the standard. Secured to the channel member 14 is a

wooden block partly engaging also the sides of the standard similarly to the U-shaped member. Secured to the block 19 is a pad or spherical portion 20 to which a hat may be secured by means of a hat pin. The padded portion 20, the channel member 14 and the lever 16 form a unit in which the channel member 14 and the lever 16 constitute a clamp for the padded member 20, the whole forming a support for the hat, which can be easily adjusted on the standard 12 as follows: The standard 12 is disengaged from the trunk, as shown in Fig. 1; by pulling upward on the padded member 20 or the standard 12 the same will be removed from the trunk. The lever 16 can then be disengaged from the standard 12 and the padded member 20 can be adjusted on the standard at any desired position. The standard 12 can then be placed in any opening 9 and in any desired side of the trunk. It is understood that a plurality of standards 12 can be used simultaneously. A special slidably locking standard may be made for engaging the opening 10 at the bottom of the trunk for carrying hats also. It is easily seen that with the structure disclosed, any size of hat, unless it is larger than the lower part of the trunk, can be placed at any desired side of the trunk and at any desired distance from the bottom of the trunk. When the standard, with the hat support thereon, is in position indicated in Figs. 1 and 6, the lever 16 cannot disengage itself from the standard, as the wall of the trunk adjacent the standard prevents it. Lateral displacement of the standard 12 is prevented by the lid of the trunk engaging the U-shaped member 13 by forcing the same against the wall edge of the trunk.

In Fig. 5 the channel-shaped member 21, which is similar in every respect to the channel-shaped member 14, is provided with an extension 22 bent so as to form a support for the tray, that is, this extension 22 takes the place of the block 19 and the padded portion 20 above mentioned. The channel member 21 is also provided with a lever 23 similar in every respect and for the same purpose as lever 16.

When the trunk is to be used in the ordinary way four standards 12 are used, one in each corner; and each one of the standards is provided with a tray support, as shown in Fig. 5. These tray supports can be clamped on the standards at any desired distance from the bottom of the trunk, therefore, the tray can be placed at any desired distance from the bottom of the trunk, or, in other words, the tray is adjustable within the trunk. Furthermore, the extension 22 and the tray support can be provided with a side lip, if desired, so that a tray shorter than the entire length of the trunk can be accommodated in the same. Consequently

the standard 12 can be placed at a proper distance from the wall so that the lip of the tray support 22 will engage the side of the tray not adjacent the wall of the trunk and thereby will prevent its side displacement in the trunk. 70

The standards 12 may be provided with hat carriers and also with tray carriers, that is, the tray carrier being above the hat carrier, after the hats have been secured in the proper place, the tray supports can be adjusted on the standards, because it is not necessary to have the standards exactly in the corner to support the tray. The standard 12 can have the side, where the lever 16 comes in engagement with it, waved so as to give a better hold to the support for the tray or hat. 75 80 85

Having thus described my invention, what I claim as new and desire to secure by Letters Patent is:

1. In a trunk, a corner rail having openings therein, a standard engaging said openings and trunk, said standard being adapted to receive a plurality of supports simultaneously, and a support on said standard; said standard being adapted to be positioned in any part of the trunk adjacent the body thereof. 90

2. In a trunk, a rail having openings therein, a standard removably associated with said rail and trunk and adapted to engage the opening of the rail, and a support projecting laterally from said standard and mounted to slide between the ends thereof. 95 100

3. In a trunk, a corner rail having openings therein; a standard removably associated with said trunk engaging said openings with one end and with the other end engaging said trunk; and a support slidably mounted on said standard. 105

4. In a trunk, a corner rail having openings therein; a standard removably associated with said trunk having a reduced end adapted to engage the openings in the rail; means at the opposite end of the standard adapted to engage the wall of the trunk; and a support on said standard, said support having clamping means whereby said support can be adjusted on said standard. 110 115

5. In a trunk, a corner rail, said rail having openings therein; a standard removably associated with the trunk; said standard having a reduced end adapted to engage the openings in the rail; a U-shaped member at the opposite end of the standard adapted to engage the wall edge of the trunk; a support on said standard; and a clamping member on said support whereby said support is secured at any desired place on said standard. 120 125

6. In a trunk, a corner rail adjacent the bottom and the sides thereof, said rail having openings therein; a standard removably associated with the trunk, said standard having a reduced end adapted to engage the 130

openings in the rail; a U-shaped member at the opposite end of the standard adapted to engage the wall edge of the trunk; a support on said standard; and a clamping member on said support whereby said support is secured at any desired place on said standard, said U-shaped member of the standard being adapted to be engaged by the lid of the trunk thereby preventing the standard from displacement in the trunk.

7. In a trunk, a corner rail adjacent the bottom and the sides thereof, said rail having openings therein; a standard removably associated with said trunk having a reduced end adapted to engage the openings in the rail; a U-shaped member secured to the opposite end of the standard adapted to engage the wall edge of the trunk whereby said standard is adjacent the wall of the trunk; a support engaging said standard; a clamping member on said support engaging said standard and whereby said support is secured to said standard, said clamping member having means whereby when said support is secured to said standard in said trunk said clamping means is prevented from displacing itself by the wall of the trunk, said U-shaped member of the standard being adapted to be engaged by the lid of the trunk, thereby preventing the lateral displacement of the standard in the trunk.

8. In a trunk, a corner rail adjacent the bottom and the sides thereof, said rail having openings therein; a standard removably associated with said trunk, said standard engaging an opening of the rail at one end; means at the opposite end of the standard adapted to engage the wall edge of the trunk and the lid of the trunk; and a support slidably mounted on said standard, said support having means whereby said support can be secured to said standard.

9. In a trunk, a corner rail adjacent the bottom and the sides thereof, said rail having openings therein; a standard removably associated with the trunk, said standard having a reduced end adapted to engage the openings in the rail; a U-shaped member at the opposite end of the standard adapted to engage the wall edge of the trunk; a support on said standard; a clamping member on

said support whereby said support is secured to said standard, said clamping members and standard having means adapted to register, said U-shaped member of the standard being adapted to be engaged by the lid of the trunk.

10. In a trunk, corner rails having openings therein, a standard adapted to engage the openings of the rails, said standards being adapted to receive simultaneously a plurality of supports, and a support on said standard mounted to slide between the ends thereof.

11. In a trunk, a corner rail adjacent the bottom and sides thereof, said rail having openings therein; a standard removably associated with said trunk having a reduced end adapted to engage the openings in the rail and a series of longitudinally disposed openings; a U-shaped member secured to the opposite end of the standard adapted to engage the wall edge of the trunk whereby said standard is adjacent the wall of the trunk; a support engaging said standard; a clamping member on said support engaging said standard; a pin on said clamping member adapted to engage the openings in the standard, said U-shaped member of the standard being adapted to be engaged by the lid of the trunk thereby preventing the lateral displacement of the standard in the trunk.

12. In a trunk, corner rails having openings therein, a standard adapted to engage the openings of the rails, and a support projecting laterally from said standard and adjustably and removably positioned between the ends thereof.

13. In a trunk, a standard, a support projecting laterally from said standard and adjustably mounted thereon between the ends thereof, and means carried by the trunk adapted to be removably engaged by the standard.

In testimony whereof I have signed my name to this specification in the presence of two subscribing witnesses.
